RUBBER HEEL

John F. Anderson, Chicago, Ill.

Application December 4, 1939, Serial No. 307,497

5 Claims. (Cl. 36—36)

This invention relates to footwear and has special reference to a rubber heel and means for detachably securing it to a shoe.

One important object of the invention is to provide a novel heel and fastening or securing means therefor wherein the parts cooperate to hold the heel in place mechanically and without the use of adhesives, nails, screws or other arrangements more or less permanently securing the heel.

A second important object of the invention is to provide an improved heel and fastening which may be assembled by hand without the use of tools.

15 A third important object of the invention is to provide a novel arrangement of means to prevent accidental displacement of the heel from the shoe.

With the above and other objects in view, as 20 will presently be apparent, the invention consists in general of certain novel details of construction and combinations of parts hereinafter fully described, illustrated in the accompanying drawings, and particularly pointed out in the appended claims.

In the accompanying drawings, like characters of reference indicate like parts in the several views, and

Figure 1 is a perspective view of a portion of a shoe with the improved heel applied thereto, the view showing the underside of the shoe.

Figure 2 is a section on the line 2—2 of Figure 1.

Figure 3 is a perspective view of the heel removed and partly broken away, the view showing the upper surface of the heel.

Figure 4 is a bottom plan view of a securing plate used in this invention.

Figure 5 is a perspective view similar to Figure 1 but showing a modified form of the invention.

Figure 6 is a section of the modified form similar to Figure 2.

Figure 7 is a section through the rubber heel on the line 7—7 of Figure 6.

45 Figure 8 is a plan view of a serrated plate used in the modified form.

Figure 9 is an enlarged cross-section of a certain rib used herein.

Figure 10 is a plan view of a plain plate used 50 in the modified form.

Figure 11 is an inverted perspective view of a third form of the invention.

Figure 12 is a vertical section on the line 12—12 of Figure 11 and showing the plate used in this 55 form in its arched position.

Figure 13 is a view similar to Figure 12 but showing the plate flattened.

Figure 14 is an inverted perspective view showing a fourth form of the invention.

Figure 15 is a vertical section on the line 15—15 of Figure 14.

In each of the forms of the invention here shown, there is illustrated the rear portion of a shoe 10 having a sole 11. At the heel of the shoe, there is secured to the underside of the sole 11, 10 a plate 12, having the usual horse-shoe shaped outline to conform to the shoe heel. This plate is permanently fixed to the sole 11 by any suitable holdfast means, such as are here indicated by the clinched nails 13. Around the curved 15 portion of the plate periphery extends an upstanding and inwardly turned flange 14. Carried by the underside of the plate is a headed securing rib indicated in general at 15 and the details of which are best seen in Figure 9. As there 20 shown, the rib has a base member 16, from which extends a stem 17 carrying a head 18, the upper surface of which is bevelled anticlinally from the center line. The rib thus has a section similar to a railroad rail or a collar button. The rib 25 extends substantially parallel to the flange 14, but terminates, as shown in Figure 4, in spaced relation to the forward or breast edge 19 of the plate 12. The rib may be integral with the plate or may be welded or otherwise secured thereto. 30

In the form of the invention shown in Figures 1, 2 and 3, the rubber heel 20 is of the usual general shape, but around the sides and back of the heel extends a groove 21 for the reception of the inturned edge of the flange 14. Also, the heel is 35 provided with a horse-shoe shaped slit 22 which extends from the top face of the heel toward the bottom face thereof but terminates in spaced relation to said bottom face. This slit 22 also terminates at its ends in spaced relation to the 40 forward face or breast 23 of the heel so that the slit 22 conforms in location to the rib.

In using this form of the invention, the rubber heel is simply positioned with the top edge of the rib 15, registering with the slit 22, and the heel 45 is then pressed firmly onto the plate 12. As this is done, the inturned portion of the flange 14 enters the groove 21. The rib 15 enters the slit 22 and compresses the rubber between the flange 14 and the rib, so that the engagement between 50 the flange and the heel is highly effective. Also, the head 18 of the rib assists materially in securing the heel in place since the elastic rubber engages in the spaces between the head 18 and base 16 at each side of the web 17.

In the form of the invention shown in Figures 5 to 8, the rubber heel 24 is of horse-shoe shape, thereby leaving a space between the arms, so that not only is efficiency against slipping effected, but economy of cost in material and manufacture is also obtained. As in the first form, this heel is provided with a groove 25 and a slit 26. A groove 27 is also formed on the inner sides of the legs of the horse shoe, the ends of this groove 10 terminating in spaced relation to the breast ends 28 of the rubber heel 24. This heel is applied as before, but due to its horse-shoe shape, the rubber between the rib 15 and the space within the horse shoe would tend to spring away from 15 the rib 15 and thus the heel would not be properly and securely held in place for use. Accordingly, to prevent this loosening action, a spreader plate 29 is provided, which fits at the side and rear portions of its periphery in the groove 27 20 and forces the part of the heel lying inwardly of the rib 15 outwardly into firm engagement with said rib. In order to prevent accidental release of the plate 29 by forward movement, it is preferred to provide forwardly facing serrations 30 on the sides of the plate. To enable the plate 29 to be manually removed from the groove 27, a finger hole 31 is provided in the plate. 25

In each of these forms, a worn rubber heel may be gripped by the fingers and removed, a 30 pry of some sort being used, if necessary. In the second form, the removal of the plate 29 may be first effected by inserting a finger in the hole 31 and pulling forwardly. If this is done, the rubber heel will be easier to remove.

35 In the form of the invention shown in Figures 11, 12 and 13, there is provided a metal plate 32, which may be secured to the shoe sole 11 as by holdfast means 33, as shown in Figure 12. Obviously this plate may be similarly secured to an 40 upper heel portion for high-heeled shoes, such as are worn by women.

The plate 32 is provided at its sides and rear with a flange 34, having at its free edge an inwardly projecting bead 35. In this form, there 45 is used a horse-shoe-shaped rubber member 36, having the portion next the plate 32 rabbeted, as at 37, and provided with a groove 38, so that the member 36 may fit snugly within the space bounded by the flange 34, while having its exterior side and rear face flush with the exterior 50 surface of the flange 34. The inner side of the member 36 is rabbeted at the portion remote from the plate 32, as shown at 39. This provides an inwardly extending shelf-like portion 40, and at 55 the junction of the portion 40 and the vertical face of the rabbet, there is provided a groove 41. A normally arched or bowed spring metal plate 42 is of such dimensions as to have its side and rear edge portion rest on the shelf 40, free from 60 the bottom of the groove 41, but when this plate 42 is flattened, as in Figure 13, its side and rear portions engage the bottom of the groove 41 and tend to spread the member 36 outwardly so as to hold it firmly in position against the flange 34, with its outer groove 38 engaging over the bead 35, thereby preventing disengagement of 65 these parts. In order to flatten the plate 42, a screw 43 is carried by the plate 32 and extends through an opening in the plate 42, so that a 70 nut 44 may engage on the screw at the side of the plate 42 remote from the plate 32. Rotation of the nut from the position shown in Figure 12 to that shown in Figure 13 thus flattens the plate 42. With the plate in this flattened condition, it presses strongly against the portion 40

of the member 36 and serves as an added means for holding the member 36 on the plate 32.

In the form of the invention shown in Figures 14 and 15, the metal plate 32 is also used, but in place of the horse-shoe-shaped member 36, there 5 is provided a heel-shaped rubber member 45 having a substantially central wall or recess 46, formed in its bottom face. An opening 47 leads from the center of the recess 46 and opens 10 through the top face of the member 45 to receive the screw 43. A washer plate 48 fits in the recess 46 and the screw 43 passes through the washer plate and carries the nut 44 as in the previous form.

The exterior of the member 45 is rabbeted at 49 15 and grooved at 50 as in the preceding form.

It will be noted that both the plate 48 and the plate 42 constitute retaining plates, screw held to the metal plate or base plate 32, and that they both rigidly resist inward flexure of the 20 outer sides of the rubber members just as do the ribs 15 and plate 29 or 39.

By removing the nut 44 in either of these forms, the plate may be removed from the screw and the sides of the rubber member flexed inwardly 25 to free the member from the flange, thus permitting a new rubber member to replace an old or worn member.

It is to be understood that the attachment may 30 be attached to high heels, such as used on ladies' shoes in lieu of being attached directly to the rear or heel end of a shoe.

What is claimed is:

1. A renewable heel structure including a plate 35 adapted for permanent attachment to the underside of a shoe at its heel portion, a flange extending from the periphery of the plate at the sides and rear thereof and having an inturned free edge, a rib on said plate substantially parallel to said flange, a rubber heel of substantially 40 the same outer contour as the plate and having a peripheral groove wherein said inturned edge engages, said heel having a slit to receive said rib, said rib constituting means to compress the rubber against the flange, said rubber heel having 45 a forwardly opening gap between its sides and the wall of said gap being provided with a groove at the sides and rear of the gap, and a spreader plate fitted removably in said gap to engage in said groove. 50

2. A renewable heel structure including a plate adapted for permanent attachment to the underside of a shoe at its heel portion, a flange extending from the periphery of the plate at the sides and rear thereof and having an inturned 55 free edge, a rib on said plate substantially parallel to said flange, a rubber heel of substantially the same outer contour as the plate and having a peripheral groove wherein said inturned edge engages, said heel having a slit to receive said 60 rib, said rib constituting means to compress the rubber against the flange and having a shank provided with a head of greater width than the shank, said rubber heel having a forwardly opening gap between its sides and the wall of said gap 65 being provided with a groove at the sides and rear of the gap, and a spreader plate fitted removably in said gap to engage in said groove.

3. A renewable heel structure including a plate 70 adapted for permanent attachment to the underside of a shoe at its heel portion, a flange extending from the periphery of the plate at the sides and rear thereof and having an inturned free edge, a rib on said plate substantially parallel to said flange, a rubber heel of substantially 75

the same outer contour as the plate and having a peripheral groove wherein said inturned edge engages, said heel having a slit to receive said rib, said rib constituting means to compress the rubber against the flange, said rubber heel having a forwardly opening gap between its sides and the wall of said gap being provided with a groove at the sides and rear of the gap, and a spreader plate fitted removably in said gap to engage in said groove, said spreader plate having forwardly facing serrations at its side edges.

4. A renewable heel structure including a plate adapted for permanent attachment to the under-side of a shoe at its heel portion, a flange extending from the periphery of the plate at the sides and rear thereof and having an inturned free edge, a rib on said plate substantially parallel to said flange, a rubber heel of substantially the same outer contour as the plate and having a peripheral groove wherein said inturned edge engages, said heel having a slit to receive said rib, said rib constituting means to compress the

rubber against the flange and having a shank provided with a head of greater width than the shank, said rubber heel having a forwardly opening gap between its sides and the wall of said gap being provided with a groove at the sides and rear of the gap, and a spreader plate fitted removably in said gap to engage in said groove, said spreader plate having forwardly facing serrations at its side edges. 5

5. A renewable heel structure including a plate adapted for attachment to the under side of a shoe at its heel portion, a flange extending from the periphery of the plate at the sides and the rear thereof and having an inturned free edge to seat in a corresponding channel in the heel, 10 and means cooperating with the heel and exerting a lateral pressure in both directions from the longitudinal center of the heel to interlock the heel and the inturned rib, said means interfitting with and actually engaging within the heel in its 15 operative position. 20
